UNITED STATES PATENT OFFICE.

JOHN DARBY, OF SUMMIT, NEW JERSEY, ASSIGNOR, BY MESNE ASSIGNMENTS, TO SHUR LOC ELEVATOR SAFETY CORPORATION, OF NEWARK, NEW JERSEY, A CORPORATION OF NEW JERSEY.

ELEVATOR.

Application filed October 5, 1926, Serial No. 139,603. Renewed September 30, 1927.

In an application of Thomas L. Harrison, Serial No. 98,995, filed April 1, 1926, assigned to the Shur Loc Elevator Safety Company, the assignee herein, there are shown, described, and claimed interlocking safety devices by which movement of the elevator car is prevented when the shaft door is open or its effective movement has been begun, the construction being such that effective opening movement of the shaft door can be commenced only when the car is at the corresponding floor, the door being at all other times (except in emergency) locked against effective opening movement, and that the locking of the controller is effected by the movement of the shaft door without involving any pressure or reaction in the movement of the controller handle. In that construction it is necessary, in order that the door may have full opening movement, that the car be at a floor in order that a part carried by it may offer resistance to the preliminary movement of a part moving with the door in order that such part may be released so as to have and to permit the door to have full opening movement. The mechanism in which the present invention is embodied, as to its principal feature, has the same characteristic of operation as that just described, but in a somewhat different mechanical expression. It will be more fully explained hereinafter with reference to the accompanying drawings in which it is illustrated and in which:

Figure 1 is a view, as seen from above, showing a portion of a shaft door, a portion of an elevator car with its controller connections, and the improved interlocking devices, the shaft door and associated parts being shown in the positions which they assume when the door is closed.

Figure 2 is a view of the same in elevation, as seen from the right hand in Figure 1, with the wall of the car removed, the notched controller and the controller rod with its operative connections being also shown.

Figure 3 is a detail view in elevation of the forked lever which is mounted on the floor sill and is engaged by the door, with some of its associated parts.

Figure 4 is a detail view in sectional elevation on the plane indicated by the broken line 4—4 of Figure 1, but on a larger scale.

Figure 5 is a detail view in sectional ele-

vation of the emergency releasing device, 55 the plane of section being indicated by the broken line 5—5 of Figure 4.

Figure 6 is a detail view in section on the plane indicated by the broken line 6—6 of Figure 3.

The interlocking devices are shown in operative relation with one member *a* of a two-part or two-speed shaft door, but it will be understood that such devices operate in the same manner whether the door is a single 65 door or is made up of several members.

In a suitable bracket *b* secured to each floor in proximity to the rear edge of the door *a*, when in its closed position, is mounted a forked lever *c* for engagement with the roller bearing stud *a*² carried by the door *a*. In the closed position of the door the forked lever stands in the position shown by full lines in Figure 3, and as the effective opening movement of the door begins the lever 75 *c* is swung from the full line position to the successive positions indicated by broken lines, the stud, in the continued movement of the door, passing over and beyond the right-hand member of the forked lever. 80 The latter remains in this position until, in the last of the closing movement of the door, the stud *a*² strikes the left-hand member of the forked lever and restores the lever to its initial position. Lugs *c*¹ on the lever coact 85 with lug *b*¹ on the bracket *b* to limit the movement of the lever. Connected with the lever *c*, as at *c*², is a connecting rod *d* which, at its other end, is operatively connected, as through a bell crank lever *d*¹, with a slide 90 *e* mounted in a guide *e*¹. The slide *e*, mounted on the door sill or floor, carries a dog *f*, which is held normally by a light spring *f*¹ or by its own weight, in position to engage a fixed shoulder *e*² on the guide housing *e*¹, 95 the dog *f*, when in engagement with such shoulder, preventing the full sliding movement of the slide *e* and therefore the effective opening movement of the door, which is connected with the slide, as already described. Also mounted in the slide *e* is a two-part plunger *g*, *g*¹, the two parts having a relatively stiff spring *g*² interposed between them and the part *g*¹ having an adjustable toe *g*³ for cooperation with the tail 100 *f*² of the dog *f*. It will be obvious that the door will be locked against effective opening movement until the plunger *g*, *g*¹ is

105

- moved so as to disengage the dog f from the fixed shoulder e^2 . Such movement cannot take place, as will be explained presently, unless the car is at the floor to offer the resistance which is necessary, in the preliminary movement of the door, as through the first inch, to the relative movement of the two-part plunger with respect to the slide, against the pressure of the light spring f^1 , to effect the disengagement of the dog f so as to permit a full opening movement of the slide and of the door. It will be understood that the plunger is formed in two parts with an interposed spring to permit movement of the slide under a condition to be explained.
- The controller i which is constructed as usual, except as hereinafter explained, coacts in substantially the usual manner with the locking rod n . The latter is carried by a suitable counter-balanced arm m^3 which is fixed on a shaft m^1 , supported in a bracket m^2 , and carries an arm m . The latter is connected by a link l with one arm of a bell crank lever l^1 , the other arm of which is in operative engagement with a sliding block o , supported for sliding movement on the car by suitable guides o^1 . Mounted on the block o , so as to be capable of limited sliding movement with respect thereto, is a shoe p , suitably formed for coaction with the plunger g , g^1 above mentioned, in the vertical movements of the elevator car. As shown, the shoe is carried by rods p^1 movably mounted in brackets o^2 on the block o , light springs p^2 being provided to hold the shoe p normally in extended position, but to permit it to yield to the pressure of the plunger g , g^1 .
- Mounted on the block o is a dog q which is held normally by its own weight out of engagement with a locking shoulder o^3 on the fixed support o^4 by which the block o is supported through the guide rollers o^1 . The shoe p carries a pin p^3 which is adapted to coact with the tail q^1 of the dog q to move the dog into locking engagement with the shoulder o^3 . This takes place when the block o is in its extreme forward position, to which it is moved normally by the counter weight on the arm m^3 and when, the block being in such forward position, the shoe p is caused to move in the opposite direction, relatively to the block o , by the preliminary movement of the plunger g , g^1 with the slide e , such relative movement of the shoe p causing the dog q to engage the locking shoulder o^3 so that the block o is held from movement and the shoe p , having reached the limit of its movement relative to the block o , is also held from further movement, whereby the resistance is offered to the movement of the plunger g , g^1 with the slide e , which causes that movement of the plunger g , g^1 , relative to the slide e in which it is carried, which is necessary to dis-

engage the dog f from the stop e^2 and permit the slide e to have the full effective movement necessary to full opening of the door. At this time the part g of the two-part plunger is in contact with the shoe p , which is itself at this time held from movement. Under this condition the spring g^2 permits the part g^1 of the plunger to move with respect to the part g thereof and the slide e therefore to have its full effective movement and the lever c to swing to a position to release the stud a^2 and permit the door to have its full opening movement.

The controller having been moved to the neutral position to bring the car to rest at the floor, the notch i^1 thereof is entered by the roller n^1 on the locking rod n , under the influence of the counter-weighted arm m^3 above mentioned and, the block o being then in its extreme forward position, in which it is held by the coaction of the shoe p , pin p^3 , dog q , and shoulder o^3 , the locking rod will be held in the notch i^1 and the controller will therefore be prevented from movement to start the car in either direction so long as the door is open beyond its initial movement, in which its roller a^2 has left the jaws of the forked lever c . When, however, the door is moved to its fully closed position and the forked lever has been swung to the position shown by full-lines in Figure 3, the slide e is withdrawn with the plunger g , g^1 is withdrawn from contact with the shoe p . When the shoe p is relieved of the pressure of the plunger g , g^1 , it is moved by the springs p^2 relative to the block o and the dog q is therefore permitted to drop out of engagement with the locking shoulder o^3 . The block o is therefore released and the locking rod is no longer held positively in engagement in the notch i^1 of the controller i . The controller can therefore be moved and by reason of the cammed or rounded formation of the notch i^1 , the rod is forced downward by the movement of the controller against the action of the counter-weighted arm m^3 .

It will be noted that the controller i , instead of being truly circular, is cammed off in both directions from the notch i^1 , so that the tendency of the pressure of the roller n^1 of the locking rod n , under the influence of the counter-weighted arm m^3 is to cause the controller to be returned to its neutral position, rather than to prevent, as with a braking action, the automatic return of the controller to neutral position, as would otherwise be the case if the controller were truly circular.

It may happen that in a contingency it may be desirable to permit the door a to be opened from the side of the door remote from the car when the car is not at the floor. To accomplish this, provision is made for disengaging the dog f from the locking shoulder e^2 from the hall side or remote side

of the door. As shown in Figure 5, there is arranged in cooperative relation with the dog f carried by the slide e , a cam slide r which is held normally in inoperative position by a spring r^1 . The cam slide is connected by a rod r^2 and a flexible joint r^3 with a rod r^4 , on which is carried a lug r^6 , designed, when lifted to be engaged by the left hand lug c^1 of lever c . An aperture r^5 in door a provides an opening for the insertion of any suitable instrument with which to lift the rod r^4 and bring lug r^6 into position to be engaged by lug c^1 when the lever c is rotated by the opening door movement. Movement of the rod r^4 to the left, causes cam r to lift latch f out of engagement with the fixed stop c^2 , thus permitting the full forward movement of slide c .

It will be understood that various changes in details of construction and arrangement can be made and that, except as indicated in the accompanying claims, the invention is not restricted to the particular construction shown and described herein.

I claim as my invention:

1. In an elevator, the combination of a controller formed with a locking notch, a locking rod for coaction therewith, and means acting normally to press the rod toward the controller and into engagement with the notch of the controller, the notch being cammed to force the rod out of the notch when the controller is turned and the rod is susceptible of movement.

2. In an elevator, the combination of a notched disk-like controller, a locking rod for coaction therewith, and means acting normally to press the rod toward the controller, the controller being cammed inwardly toward the notch, whereby the pressure of the rod tends to turn the controller to notch engaging position.

3. In an elevator, the combination of a car, a movable shaft door, a locking device on the car side of the door to prevent full opening movement of the door, means the operation of which is controlled by the position of the car to disengage said locking device, and other means operable from the other side of the door to disengage said locking device.

4. In an elevator, the combination of a car, a movable door, a slide movable with the door, a locking device to prevent movement of the slide and of the door, means the operation of which is controlled by the position of the car to disengage said locking device, and other means operable from the other side of the door to disengage said locking device.

5. In an elevator, the combination of a car, a movable door, a slide movable with the door, a locking device to prevent movement of the slide and of the door, means the operation of which is controlled by the position of the car to disengage said locking device, and

other means operable from the other side of the door to disengage said locking device, such means comprising a cam slide to disengage the locking device, and means to operate the cam slide.

6. In an elevator, the combination of a car, a movable door, a slide movable with the door, a dog carried by the slide and normally engaging a stop to prevent movement of the slide, a plunger carried by the slide and arranged for coaction with the dog to disengage the same from the stop, and means carried by the car for coaction with the plunger to disengage the dog and permit full effective movement of the slide and the door.

7. In an elevator, the combination of a car, a movable door, a forked lever in operative relation with the door and movable therewith in the initial opening movement of the door, a slide operatively connected with the forked lever, a dog carried by the slide and adapted to engage a stop to prevent movement of the slide, a plunger carried by the slide, and means carried by the car for coaction with the plunger to disengage the dog from the stop and permit full effective movement of the slide and of the door.

8. In an elevator, the combination of a car, a movable door, a controller on the car, a locking rod, means to press the locking rod normally toward the controller, a sliding block operatively connected with the locking rod and movable therewith, a dog carried by the block and adapted to engage a stop to prevent movement of the block and of the locking rod, but normally disengaged therefrom, and means actuated by the opening movement of the door to actuate the dog to engage the stop and prevent movement of the block and of the locking rod.

9. In an elevator, the combination of a car, a movable door, a controller on the car, a locking rod, means to press the locking rod normally toward the controller, a sliding block operatively connected with the locking rod and movable therewith, a dog carried by the block and adapted to engage a stop to prevent movement of the block and of the locking rod, but normally disengaged therefrom, and means actuated by the opening movement of the door to actuate the dog to engage the stop and prevent movement of the block and of the locking rod.

10. In an elevator, the combination of a car, a movable door, a notched controller on the car, a locking rod, means to press the locking rod into the notch of said controller, a sliding block operatively connected with the locking rod and movable therewith, a dog carried by the block and adapted to engage a stop when the locking rod is in the

notch of said controller and prevent movement of the block and of the locking rod, and means actuated by the opening movement of the door to actuate the dog to engage the stop and prevent movement of the block and of the locking rod, such means including a shoe mounted movably on the block for coaction with the dog to move it to locking position.

10. 11. In an elevator, the combination of a car, a notched controller on the car, a lock-

ing rod to engage said controller notch, means carried by the car to operate the locking rod, a movable door, a slide movable with the door to engage said last named means to hold the locking rod against movement and lock the controller in the opening movement of said door.

This specification signed this 1st day of October, A. D. 1926.

JOHN DARBY.
